UNITED STATES PATENT OFFICE.

THEODORE C. WHEATON, OF MILLVILLE, NEW JERSEY.

DESIGN FOR A BOTTLE.

SPECIFICATION forming part of Design No. 22,354, dated April 18, 1893.

Application filed February 25, 1893. Serial No. 463,760. Term of patent 3½ years.

To all whom it may concern:

Be it known that I, THEODORE C. WHEATON, a citizen of the United States, residing at Millville, in the county of Cumberland and State of New Jersey, have invented a certain new and original Design for Bottles, of which the following is a specification, reference being had therein to the accompanying drawings, in which—

- 10 Figure 1 is a side elevation, Fig. 2 an edge elevation and Fig. 3 a transverse section of the new bottle.

The cylindrical neck a of the bottle is formed with a flange a' as usual, and the enlarged body b is substantially flat, its sides being concaved slightly and its vertical edges being depressed their entire length to form rounded grooves or flutes b' , the ends of the flutes rounding smoothly into the upper and

lower rounded corners b'' . The upper shoulder b'' extends entirely around the upper end of the body and is rounded or convexed nicely into the sides thereof, and the lower end of the body is contracted to form the lower convexed corner or shoulder b'' , the contracted base b^3 having formed on it an annular flange or bead b^3 . The four vertical corners b^2 are also convexed as shown.

I claim—

The design for a bottle substantially as herein shown and described.

In testimony whereof I affix my signature in presence of two witnesses.

THEODORE C. WHEATON.
